PATENTED AUG. 13, 1907.

M. WATERS.

SWITCH RAIL CONNECTION.

APPLICATION FILED APR. 18, 1907.

UNITED STATES PATENT OFFICE.

MINOR WATERS, OF NEW ALBANY, INDIANA.

SWITCH-RAIL CONNECTION.

No. 862,950.

Specification of Letters Patent.

Patented Aug. 13, 1907.

Application filed April 18, 1907. Serial No. 368,967.

To all whom it may concern:

Be it known that I, MINOR WATERS, a citizen of the United States, residing at New Albany, in the county of Floyd and State of Indiana, have invented a new 5 and useful Switch-Rail Connection, of which the following is a specification.

The invention relates to improvements in switch rail connections.

The object of the present invention is to improve the 10 construction of switch rail connections, and to provide a simple, inexpensive and efficient device of great strength and durability, adapted to be applied to switch rails in a comparatively short time and capable, should the track get slightly out of gage, of being readily 15 adjusted, so that the switch points will abut solidly against the rails.

A further object of the invention is to provide an adjustable switch bar of this character, which will not require repair unless injured by a wreck, and which, 20 should an engine run through the point and twist or bend the crank of the switch-stand, will be capable of adjustment to overcome the twisted crank and enable the switch-stand to be operated within a few minutes, if the said crank is not too badly twisted or bent.

25 With these and other objects in view, the invention consists in the construction and novel combination of parts hereinafter fully described, illustrated in the accompanying drawing, and pointed out in the claims hereto appended; it being understood that various 30 changes in the form, proportion, size and minor details of construction, within the scope of the claims, may be resorted to without departing from the spirit or sacrificing any of the advantages of the invention.

In the drawing:—Figure 1 is a plan view of a switch 35 rail connection, constructed in accordance with this invention and shown applied to a portion of a track. Fig. 2 is a sectional view, taken substantially on the line $x-x$ of Fig. 1. Fig. 3 is a detail perspective view, illustrating the adjustable connection between the 40 switch rails and the connecting bar.

Like numerals of reference designate corresponding parts in all the figures of the drawing.

1 designates a transverse connecting bar, extending beneath a pair of movable switch rails 2 and 3 and connected at one end with a rod 4, which is designed to extend to a switch-stand, not shown, but any suitable means may be employed for operating the connecting bar 1, as will be readily understood.

The switch rails 2 and 3 are each connected with the 50 bar 1 by means of an adjustable connecting device, consisting of an upper plate or member 5 and a lower plate or member 6. The upper plate or member, which is arranged upon the upper face of the connecting bar

1, has an outer inclined portion 7, arranged upon the adjacent bottom flange of the rail and provided with a 55 vertically disposed attachment plate or portion 8. The vertically disposed attachment plate or portion 8, which fits against the web of the rail, extends laterally from the inclined portion to provide a pair of projecting arms, and the projecting arms or portions are pierced 60 by horizontal track bolts 9, or other suitable fastening devices, whereby the upper plate or member is securely fastened to the switch rail. The upper plate or member is secured at its inner portion to the bar 1 by means of a vertical bolt 10, which pierces the top plate and 65 which operates in a longitudinal slot 11 of the bar 1. The bolt 10 also pierces the outer end of the bottom plate or member 6, which is provided at its inner end with a longitudinal slot 12 for the reception of a bolt 13. The bolt 13 pierces the bar 1 and adjustably en- 70 gages the inner end of the lower plate or member.

The outer end of the lower plate or member is connected with the inner end of the upper plate or member by sides or flanges 14, which are preferably formed integral with the upper and lower plates or members, 75 and which coöperate with the same to provide a sleeve to slide on the bar 1. By means of the slot 11 of the bar 1 and the slot 12 of the lower plate or member 6, the device for connecting the rails to the bar 1, is adjustably secured to the latter and there is no liability 80 of the device accidentally slipping, should one of the bolts become loose. The end portions of the bar or member 1 extend beneath each of the switch rails and the adjacent fixed rails 15 and 16, and a safe and secure device for connecting the movable switch rails is provided. The device may be installed at a very small cost, and unless broken or otherwise injured by a wreck, will not require repair. The adjustment of the switch rails on the connecting bar enable such rails to be readily arranged, so that they will properly abut 90 against the fixed rails. Another advantage of the switch rail connection is that it may be installed, or the rails may be adjusted by one person and only a single wrench is necessary in such operation.

Having thus fully described my invention, what I 95 claim as new and desire to secure by Letters Patent, is:—

1. The combination with a movable switch rail, of a connecting bar extending beneath the rail and provided with a slot, an upper plate or member arranged on the connecting 100 bar and extending over the bottom flange of the switch rail and provided at the web thereof with a vertical plate or portion, said vertical plate or portion being extended laterally to form arms, which are secured to the web of the rail, a lower plate or member provided at its inner end with a slot, an outer fastening device piercing the upper and lower plates or members and operating in the slot of

the bar, and an inner fastening device piercing the bar and operating in the slot of the lower plate or member.

2. The combination with a movable switch rail, of a connecting bar extending beneath the rail, an upper plate or member arranged on the connecting bar and extending over the bottom flange of the switch rail and having an upwardly extending portion secured to the web of the rail, said plate being also provided at the side edges of the connecting bar with depending side flanges, a bottom plate or member extending inwardly from the said flanges, and

fastening devices for securing the upper and lower plates or members to the connecting bar.

In testimony, that I claim the foregoing as my own, I have hereto affixed my signature in the presence of two witnesses.

MINOR WATERS.

Witnesses:
